UNITED STATES PATENT OFFICE.

FRANZ PUENING, OF PITTSBURGH, PENNSYLVANIA.

HEATING METHOD AND APPARATUS.

Application filed July 24, 1925. Serial No. 45,815.

My invention relates to a method and an apparatus for heating retorts, lehrs, and the like, of the type wherein the heated gases are reciprocated or pulsated within the retort or other chamber.

The present invention constitutes an improvement upon the methods and apparatus disclosed in my Patents Nos. 1,542,953, 1,542,954 and 1,542,956, issued June 23, 1925, 10 wherein reciprocatory and oscillatory pistons are employed for effecting pulsation of the heated gases within a heating chamber.

In Patents No. 1,542,953 and 1,542,954 means are shown for admitting cooling gases 15 at points intermediate the piston and the body of heating gases, but such points are not closely adjacent to the exposed faces of the pistons. In Patent 1,542,954 means is shown for circulating a cooling fluid through the piston which is hollow. In both patents cooling fluid is admitted to opposite sides of the piston through separate conduits.

By means of my present invention I am 20 enabled to cool a hollow piston both interiorly and exteriorly of its walls by fluid supplied through a single conduit. The arrangement not only makes for simplicity of structure, but the piston is more efficiently cooled since a stratum of cooling fluid is created against 25 the exposed faces of the piston and relatively small volumes of cooling gas or other fluid will be sufficient, because the fluid is conducted directly to the surfaces to be cooled, and is not unnecessarily intermingled with 30 the heating gases.

A further advantage incident to my improvement arises from the fact that the heating gases are not unnecessarily cooled by intermingling of large quantities of cooling 35 fluid therewith.

Furthermore, the piston in the present case is as effectively cooled at its extreme position as at its intermediate position, since the cooling fluid is conducted directly to the 40 surface thereof at all stages of movement.

The present arrangement avoids the necessity of applying heat insulating material to the faces of the piston, thus not only saving the expense of such material, but avoiding 45 the labor and expense of securely maintaining the material in place, and at the same time reducing the weight of the piston which is important for big pistons.

One object of the present invention is to 50 provide a piston wherein the walls which are exposed to the hot gases are in the form

of diaphragms and wherein such walls are maintained under tension to prevent rattling or vibration thereof, and the piston may furthermore be of relatively light weight. 60

Another object of my invention is to simplify and improve generally the structure and operation of devices of the class referred to.

Some of the forms which my apparatus 65 may take and by means of which the method may be practiced are shown in the accompanying drawing, wherein Fig. 1 is a vertical sectional view of apparatus embodying my invention; Fig. 2 is a plan view of a portion of 70 the framework of the piston of Fig. 1; Fig. 3 is a view, on an enlarged scale, of a portion of the apparatus of Fig. 1; Fig. 4 is a vertical sectional view of a modified form of device for supplying cooling gases to the dia- 75 phragm of Fig. 1; Fig. 5 is a side elevational view of an oscillatory piston embodying my invention; Fig. 6 is an enlarged sectional view taken on the line 6—6 of Fig. 5; Fig. 7 is a sectional view taken on the line 7—7 of 80 Fig. 5, and Fig. 8 is an enlarged sectional view taken on the line 8—8 of Fig. 5.

In Fig. 1 I have shown a chamber 10 in which is mounted a piston 11 that may be reciprocated vertically by a rod 12 which is 85 connected to any suitable mechanism for effecting reciprocation thereof. The piston 11 has snug-fitting engagement with the vertical walls of the chamber 10 so that as it is reciprocated the heated gases will be caused to 90 flow through passages 13 in the direction indicated by the arrows when the piston is moving downwardly, and in the opposite direction when the piston is moved upwardly, thus effecting circulation of the gases in desired 95 directions through a heating chamber (not shown) after the manner shown in the patents above referred to.

As stated above, my invention is in part directed to means for maintaining a cooled 100 area upon the exposed faces of the piston. In order to accomplish this I construct a piston of hollow form and perforate the walls thereof and also provide means for supplying cooling liquid to the interior of the piston. The 105 piston is composed of tubular radially projecting members 14 arranged in the manner of spokes. At their inner ends the members 14 are rigidly connected to an annular metallic sleeve 15 which is in turn rigidly secured between upper and lower plates 16 by bolts 17 or otherwise. The walls 15 and 16

together form a header chamber with which the tubular members 14 communicate. The spokes 14 are secured to and communicate at their outer ends with a pipe ring 18, such pipe ring being provided with two series of perforations 19 throughout its circumference as shown more clearly in Figs. 2 and 3.

The outer side of the pipe ring 18 is preferably covered with heat insulating material 20 that is held in place by a channel band 21 of annular form. Frame members 22 of annular form are welded or otherwise secured to the pipe ring 18 and are riveted to the band 21.

15 Diaphragm-like members 23 form the upper and lower walls of the piston 11. These diaphragms are preferably of thin metal such as nickel, and are riveted at their peripheries to the frames 22, while at their inner edges they are held tightly against the members 16 by the bolts 17. The diaphragms 23 are provided with a suitable number of perforations 24 through which cooling gas may escape as hereinafter explained.

25 The header chamber formed by the members 15—16 is welded or otherwise secured to a hollow piston rod 25 that is perforated to provide communication between the interior of the rod and the said header chamber. A 30 plug 25^b is placed in the hollow rod 25, to prevent flow of gas to the lower end thereof.

The upper end of the rod is connected to the rod 12 that is actuated as above explained to effect vertical reciprocation of the piston. 35 The rod 12 extends into a chamber 26 with which communicates a supply pipe 27 through which a cooling gas enters said chamber. This gas then flows through the perforations in the upper end of the pipe or hollow rod 25; thence into the header chamber; through the spoke-like members 14; to the pipe ring 18; through the perforations 19 and thence through the perforations 24. The piston rods 12 and 25 operate through stuffing boxes or glands so that gases will not escape from the chambers 10 and 26.

40 The cooling gas is supplied under pressure greater than that at the advancing side of the piston so that flow thereof will be constant. As the cooling gas emerges from the perforations 24 it will spread over the outer surface of the diaphragms 23 as indicated in Fig. 1 by the shaded lines 28. A zone of cooling gas is thus maintained adjacent to the faces of the piston, and the piston thereby protected from the hot gases which it is employed to circulate. Owing to the fact that the cooling gas is supplied under pressure, the diaphragms 23 are maintained under tension, thus preventing rattling thereof.

45 Referring to Fig. 4, I show another means of supplying cooling gases to the piston. In this structure a hollow piston rod 25^a may be connected only to the lower side of the piston and the various connections above the

piston of Fig. 1 dispensed with, save for the operating rod, such as 12.

The lower end of the conduit 25 is connected to a valve chamber 30 that functions as a piston, within a cylinder 31. A fluid supply pipe 32 communicates with the upper and lower ends of the cylinder 31 through pipe connections 33 and 34, respectively, that are provided with flap valves at their ends. The valve chamber 30 communicates with opposite sides of its piston-like flange 35 through flap valves. It will be apparent that as the piston 35 moves down the flap valve of pipe 33 will be closed and flap valve 36 of the piston opened so that a flow of gas will be set up in the pipe 25^a. Upon upward movement of the piston 35, the flap valve of pipe 33 will be closed and the positions of the other flap valves reversed, so that gas from the upper portion of the cylinder 31 will be forced upwardly through the conduit 25^a.

50 Referring now to Fig. 5, I have shown my invention as applied to a piston of the oscillatory type, such for example, as that shown in Fig. 1 of my Patent No. 1,542,956. In this structure the piston is mounted upon a hollow shaft 39 through which cooling gas may be supplied under pressure, in the direction indicated by the arrows and which serves as a header chamber. A series of pipes 40 extend downwardly from the interior of the shaft 39, being secured thereto in any desired manner. The upper ends of these pipes are perforated as indicated at 41 so that gas flowing through the shaft 39 will enter the 55 pipes 40. The pipes at their lower ends communicate with a header 42 which is in turn perforated at a series of points 43. A plurality of diaphragm-like metallic plates 44 are secured at their vertical edges to the pipes 40 by means of bars 45 that are held in place by bolts 46 as shown more clearly in Fig. 8. The upper edges of these plates 44 are held in position by means of bars 47 and bolts 48, while their lower edges are securely held by bars 49 and bolts 50. The plates 44 are provided with perforations 51 at suitable distances. A bar 53 is disposed between the upper ends of each of the pipes 40 and may be welded to the hollow shaft 39 as shown in Fig. 6.

60 It will be seen that as the cooling gas flows through the hollow shaft 39 it will enter the various pipes 40 and will then flow to the header 42. From the header 42 the gases will flow through the openings 43 and 51, to provide a film or zone of cooled gas against each face of the piston, as in the case of Fig. 1. If desired, perforations 52 may also be provided in the sides of pipes 40 so that gases may flow 65 directly therefrom to the diaphragm plates.

65 It will be understood that the relative diameters of the openings or perforations 41—43—51—52, with respect to each other and with respect to the diameters of the pipes 44 70

and conduit 39, are such that there will be proper distribution of cooling gas throughout the entire area of the piston.

Should the ribs and bolts which hold the plates 23 and 44 in position, be loose or leakage of fluid occur beneath the edges of the plates, no harmful effect will be produced since it is desired to have flow of cooling fluid from the interior of the pistons to the exterior thereof. The number of perforations 34 and 51 in the plates can be calculated as to number and diameter to compensate for such leakage.

No provision need be made for carrying off the cool gases that emerge through the perforations of the piston, since such gases as they become heated and lose their cooling function, will mingle with the heating gases and are exhausted through the furnace stack.

In certain cases mainly where gas is used for heating, air could be employed as cooling fluid. Having emerged through the perforations of the piston, the air will in its further course of travel mingle with unburned fuel gases and thus be consumed, so that only combusted gases leave the furnace.

I claim as my invention:

1. The method of cooling a chambered member employed in actuating heated gases, which comprises conducting relatively cool fluid to the interior and exterior walls of said chambered member simultaneously.

2. The method of cooling a member employed in actuating heated gases, which comprises forming a stratum of relatively cool fluid upon the exposed surfaces of said member.

3. The method of cooling a hollow piston having perforated walls which comprises actuating said piston to effect movement of heating gases, and supplying a cooling fluid under pressure to the interior of said piston.

4. The method of cooling a hollow piston having perforated walls which comprises actuating said piston to effect movement of heating gases, and supplying a cooling fluid to the interior of said piston under pressure greater than the maximum pressure imposed upon said heating gases by movement of the piston.

5. The method of cooling a piston, which comprises actuating said piston to effect movement of heating gases, creating a substantially constant flow of cooling gas to the exposed surfaces of said piston, and permitting said cooling gas to mingle with the heating gases.

6. The method of cooling a hollow piston having thin walls which compress actuating said piston to effect movement of heating gases, and supplying a cooling fluid to the

interior of said piston under pressure greater than the maximum pressure imposed upon said heating gases by movement of the piston. 65

7. The combination with a chamber adapted to receive heated gases, of means for effecting movement of said gases, comprising a piston, and means for creating a strata of relatively cool gas upon surfaces of the piston 70 which are exposed to the heated gases.

8. The combination with a chamber adapted to receive heated gases, of means for effecting movement of said gases, comprising a piston, and means for setting up a flow of 75 cooling fluid across that surface of the piston which is exposed to the heated gases.

9. The combination with a chamber adapted to receive heated gases, of means for effecting movement of said gases, comprising 80 a chambered piston having perforations in its walls, and means for supplying cooling fluid under pressure to said chambered piston.

10. The combination with a chamber 85 adapted to receive heated gases, of means for effecting movement of said gases, comprising a chambered piston having perforations in its walls, a hollow piston rod for actuating said piston, and means for supplying cooling 90 fluid through said piston rod to said piston.

11. The combination with a chamber for heated gases, of means for effecting movement of gases within the chamber, comprising a piston composed of a frame-work having thin metallic plates secured to opposite sides thereof, and means for conducting fluid to the space between said plates, the plates being provided with perforations to permit escape of said fluid. 95

12. The combination with a chamber for heated gases, of means for effecting movement of gases within the chamber, comprising a piston composed of a frame-work having thin metallic plates secured to opposite 100 sides thereof, and means for conducting fluid under pressure to the space between said plates, to thereby maintain the plates under tension.

13. The combination with a chamber for 110 heated gases, of means for effecting movement of gases within the chamber, comprising a piston composed of a frame-work having thin metallic plates secured to opposite sides thereof, and means for conducting fluid 115 under pressure to the space between said plates, to thereby maintain the plates under tension, the said pressure being greater than the pressures to which the outer surfaces of the plates are normally subjected. 120

In testimony whereof I, the said FRANZ PUENING, have hereunto set my hand.

FRANZ PUENING.
